UNITED STATES PATENT OFFICE

128,045

DESIGN FOR AN EMBALMER'S TABLE

Ernest H. Kaiser, Chicago, Ill., assignor to Frigid
Fluid Company, a corporation of Illinois

Application October 9, 1940, Serial No. 95,717

Term of patent 3½ years

To all whom it may concern:

Be it known that I, Ernest H. Kaiser, a citizen of the United States, residing at Chicago, in the county of Cook and State of Illinois, have invented a new, original, and ornamental Design for an Embalmer's Table, of which the following is a specification, reference being had to the accompanying drawing, forming a part thereof, in which:

Figure 1 is a side elevational view; Figure 2, an elevational view; and Figure 3 is a top plan view of an embalmer's table, showing my new design.

I claim:

The ornamental design for an embalmer's table, as shown.

ERNEST H. KAISER.
